(57) **CLAIM**

The ornamental design for a wall display device, as shown and described.

DESCRIPTION

FIG. 1 is a front elevational view of the wall display device of the present invention;

FIG. 2 is a rear elevational view of the wall display device of FIG. 1;

FIG. 3 is a right side elevational view of the wall display device of FIG. 1, the left view being a mirror image thereof;

FIG. 4 is a top plan view of the wall display device of FIG.

1;

FIG. 5 is a bottom plan view of the wall display device of

FIG. 1.

The broken lines showing of words in FIG. 1 and clock hands in FIGS. 1,3,4 and 5 are for illustrative purposes only and form no part of the claimed design.

1 Claim, 3 Drawing Sheets

FIG. 2

FIG. 1

FIG. 3

FIG. 5

FIG. 4
